UNITED STATES PATENT OFFICE.

HENRY EGNER, OF CINCINNATI, OHIO.

DETACHABLE VEHICLE-SEAT BACK.

No. 907,325.

Specification of Letters Patent. Patented Dec. 22, 1908.

Application filed November 25, 1907. Serial No. 403,620.

To all whom it may concern:

Be it known that I, HENRY EGNER, a citizen of the United States, and residing at Cincinnati, Hamilton county, State of Ohio, have invented certain new and useful Improvements in Detachable Vehicle - Seat Backs; and I do declare the following to be a clear, full, and exact description of the invention, attention being called to the accompanying drawing, with the reference characters marked thereon, which forms also a part of this specification.

This invention concerns topped vehicles like buggies, run-about, phaetons, cabs, cabriolets, carts and certain types of surreys, carriages and wagons. In all or most all of such vehicles the top is connected to and supported above the seat and arranged to be detachable therefrom, so that it may be removed when there is no need or desire for its use. Tops are bulky affairs and possess little rigidity of their own, for which reason they cannot be conveniently handled after detached and do not readily hold their shape.

To overcome this difficulty and instead of being taken off independently, they are in many cases removed with the so-called seat-rail, an intermediate frame-member to which the top is attached and by which in turn it is connected to the seat, so that, when removal of the top is desired, top and seat-rail remain connected and are detached together from the seat. The top so removed with the seat-rail from the vehicle is now held in shape by the seat-rail to which it remains connected. This is satisfactory when the seat-rail is in one piece and extends continuously from one side around the rear of the seat to the other side forming a rigid, yoke-shaped frame.

When the seat-rail is in two disconnected sections, one on each side only and not continuous around the rear of the seat, as is often the case, removal in the aforesaid manner does not work well, because the two disconnected seat-rail sections do not form a rigid frame. Nor can it be done satisfactorily where the seat is provided with a back, which is generally the case, because such backs are connected in part to the seat and also in part to the seat-rail by means of the usual arm-braces and therefore the seat-rail, even if it should form a continuous frame, cannot be conveniently removed from the seat by reason of the interfering presence of the back to which it is also connected. In

both these contingencies this difficulty is now usually overcome by including also the seat in the parts to be removed, so that in such case and when use of the top is not desired, this latter is neither independently removed nor removed with the seat-rail, but seat, top, and seat-rail which connects both of them all are removed together, the top remaining in position on the seat. This requires however an extra seat without a top, to take the place of the seat so removed.

I simplify matters and do away with the requirement of an extra seat in such cases where the presence of a back, by reason of its particular connection, interferes with, or prevents the convenient detachment of the seat-rail from the seat, or where a sectional seat-rail, even if it could be detached from the seat independently of a back, would nevertheless fail to hold the top to its shape after both have been detached from the seat because of the rail not being a continuous structure. I accomplish this by providing certain means and by so arranging seat, seat-rail and back that the mere detachment of the seat-rail from the seat carries also the back with it, seat-rail and back being for this purpose connected to each other independently of the seat so as to come off together as a whole they remaining permanently connected at all times, whether in position on, or detached from the seat. Therefore if now under my improved arrangement, removal of the top is desired, it is only necessary to detach the seat-rail to which the top is connected from the seat, said seat-rail then carrying top and back with it. The seat remains in place and no extra seat is required. The back, which remains in connection with the seat-rail, furnishes the same rigidity for the purpose of holding the removed top to shape while not in use, as an entire seat would do and therefore it is further immaterial whether the seat-rail is a continuous one, reaching around all three sides of the seat, or whether it is merely a sectional one, provided on the sides of the seat only and therefore otherwise insufficient to hold the top rigid. If a back is now desired on the seat, to take the place of the one removed therefrom with the seat-rail and top, an extra back may be provided which has a similar seat-rail arranged to readily fit the seat to which it is to be connected. Thus, as will be readily seen, in vehicles having seats with backs, the re-

quirement of having to keep on hand two complete seats, one of which carries a top, is done away with by my arrangement which permits removal of the top without disturbing the seat.

5 The invention consists of the particular means and their construction whereby a back and a seat-rail are connected to each other in a manner that both together and as a whole 10 may be readily connected to, or detached from a vehicle-seat, so that a top in case one is carried by the seat-rail simply follows this latter.

15 The invention also consists of the particular means and their construction whereby these two sets of connected parts may be quickly and conveniently removed from, or attached to the seat, all without the use of tools and interchanged, the one set comprising seat-rail and back only, with the set including also the top, and vice versa.

20 In the following specification and particularly pointed out in the claims at the end thereof, will be found a full description of my 25 invention, together with its manner of use, parts and their construction which latter is also illustrated in the accompanying drawing, in which:

25 Figure 1, is a side-elevation of a vehicle-30 seat with a back in position. Fig. 2, is a vertical section through this back and through a portion of the seat. Fig. 3, is a perspective view of a part of each, of the seat and of its back, which latter is shown detached. Fig. 35 4, is an enlarged view of the rear part of the seat-rail used in connection with this back and seat. Fig. 5, in a side view of the upper part of the seat with certain parts in section, illustrates manipulation for connecting or 40 detaching the back. Fig. 6, is a view similar to Fig. 4, and illustrates particularly how the rear part of the seat-rail is attached to the upper part of the seat. Figs. 7, 8, and 9, in vertical, sectional detail views through one side 45 of the seat, illustrate manner of locking for connecting and unlocking for detaching, the front-part of the seat-rail. Fig. 10, in an enlarged, horizontal, sectional detail-view illustrates how the seat-rail is locked in position 50 after attached. Fig. 11, in a perspective view shows at reduced scale, the back and seat-rail with the vehicle-top in position but detached from the seat.

55 A, is the cushion of the seat contained within the box-shaped seat-frame of which a, indicates one of the sides, and a', is the rear-side. Brackets are connected to the inner side of the sides, preferably by bolts, there being two brackets on the rear-side, one being shown at B, and two on each side at B', and at B². These brackets project above the upper edges of the sides to which they are connected and extend horizontally outwardly therefrom as shown at b. This projecting 60 horizontal part of these brackets is slotted,

the slots in the brackets B, on the rear-side and in brackets B', on the sides next to the rear-side being parallel to each other and parallel to the sides of the seat as shown at 13. The slots in brackets B², near the front 70 of the seat are arranged at right angles to these slots first mentioned and as shown at 14.

75 C, is the cushion of the back and c, is the back-proper on which the former is supported. Angle-braces 15, are attached to the front-side of back c, and extend out below and horizontally rearwardly around the lower edge thereof. These braces are so spaced on the back that their horizontally 80 projecting portions come to a seat upon the horizontal portion b, of brackets B, on the rear-side of the seat. These portions of the braces have circular openings 16, the centers of which, when the back is in position, register with the longitudinal center lines of slots 13, in top part b, of these rear-brackets. (See Fig. 6.)

85 D, is the longer part or side of the so-called seat-rail which latter serves as the medium 90 whereby the detachable connection of the back to the seat is accomplished and to which also top 17, is connected as shown in Fig. 11. It may be a continuous rail forming 95 a yoke-shaped frame extending from one side of the seat around the back to the other side as indicated in dotted lines in Fig. 3, or it may be in two sections which extend along the upper edge of the seat on each side thereof as shown at D, and which reach also partly 100 around the back as shown at d, in said figure. These longer portions D, are also provided with studs 18—18, which project outwardly from the sides thereof as shown in Figs. 3, and 5, and serve for attachment of the top 105 17, in the usual way as shown in Fig. 11.

110 Seat-rail and back c, are connected to each other by braces constituted by arm-rests E, which latter at their upper ends are secured to the back as shown at e. At their lower ends they are perforated and engaged by a stud 19, projecting upwardly from the upper edge of the seat-rail near its front-end as best shown in Fig. 5, and integral therewith. This stud projects through and beyond this 115 perforation and receives a nut 21, at its end whereby the connection is completed as shown in Figs. 1 and 3. In addition to this, the seat-rail at its short part d, and back c, are also held together by the horizontal part 120 of braces 15, which projects outwardly beyond the lower edge of the back and is fitted into a notch 22, on the underside of said parts d, of the seat-rail. In addition there is a boss 23, on the seat-rail which projects into 125 the circular opening 16, in said brace, so that the position of the engaged parts, brace 15, and seat-rail part d, is defined in a horizontal direction. Seat-rail and back connected to each other as described are also connected to 130

the seat, this connection being a detachable one by hooks 24, 25 and 26, which project from the underside of the seat-rail on each side (hooks 26 projecting from bosses 23) and 5 all adapted to pass into the slots in the horizontal parts *b*, of brackets B, B', and B². These hooks consist each of an upright shank and a horizontal projection at the lower end of the same. These projections are arranged 10 parallel to the slots in the brackets which they are intended to enter and they are of a length nearly equal to the length of these slots so that they may freely pass in.

Fig. 5, illustrates manner of attachment of 15 combined seat-rail and back together to the sides of the seat. The parts to be attached are first brought above the seat in a position as shown in Fig. 3, after which the rear part of the seat rail with the back is lowered as 20 shown in Fig. 5, so that hooks 24, may enter slots 13, in brackets B, on the rear part of the seat. The front-part of the seat-rail is now still more lowered so that hooks 25, may also enter their slots in brackets B', on 25 the sides of the seat next to the rear-brackets, see Fig. 5, noting also Fig. 6. The seat-rail is now pulled forward, see dotted lines in Fig. 5, which causes the shanks of hooks 24 and 25, to move forward in the slots which 30 they occupy, while at the same time the projections on their lower ends pass under and engage the horizontal parts *b*, of these brackets in a manner as shown in Figs. 1, and 2. This brings hooks 26, and the horizontal parts thereof which are in a position 35 with relation to slots 14, in the brackets below, as shown in Fig. 7, also sufficiently forward to bring them fully above these slots and permits them to be lowered into them 40 as shown in Fig. 8, see also Fig. 1, and dotted lines in Fig. 5. It will now be readily understood that as soon as hooks 26, have entered slots 14, in brackets B², hooks 25, and 24 become locked in position in the slots 45 of the other brackets, that is they cannot move rearwardly again, or become disengaged. It only remains now to also lock hooks 26, in slots 14, to complete the attachment 50 of the seat-rail. This is done by spring-snaps F, provided one on each side of the seat and below front-brackets B². They are connected in a suitable manner as best 55 shown in Figs. 7, 8, and 9, being bent over the upper edge and down on the inside of sides *a*, of the seat, so as to lie under the connected part of brackets B². The bolts, or one of them, whereby these brackets are connected, serve also in each case to connect these springs. Where only one of the bolts 60 is so used, a screw 27, is substituted in each case for the other bolt, the head of such screw being covered by the brackets. The upper horizontal part of each of these springs which lies under the horizontal part *b*, of brackets B², has a slot *f*, which in length 65

equals slot 14, in part *b*, above and also registers with the same transversely, see Figs. 3, 5, and 10. Longitudinally it is out of alinement as shown in Figs. 7, 8, 9, and 10, so that a part of the solid part of the 70 spring closes a part of the slot 14, in member *b*, see Figs. 7, and 10. When hook 26, is lowered into slot 14, it encounters this solid part of the spring, and when pressure is applied from above it depresses the spring as 75 shown in Fig. 8, which depression continues until the point of the hook has passed clear through slot 14, in the bracket and becomes free to pass under the same. This movement releases also the spring and permits 80 the same to return to its normal position against the underside of the bracket. See Fig. 9. In doing this the spring closes in over the hook, engaging the same in its slot and holds it locked by confining it closely 85 against movement in any direction. There is sufficient yield in the forward parts of the seat-rail to permit the spring by its reaction, when returning to normal position, to force said hook outwardly and under the bracket 90 as soon as it has cleared slot 14, so that downward pressure by the manipulator is in most cases sufficient to effect the engagement. Lateral, that is outward, pressure may however be added at the same time if 95 necessary to aid the springs to find the locking position. When so locked, the shanks of hooks 26, occupy the outer part of slots 14, as shown in Figs. 9, and 10, while the hooked projections thereon occupy slots *f*, in the 100 spring-snaps below. It will be noted, when the seat-rail is so attached, that braces 15, of back *c*, are also firmly held in position between the rear parts *d*, of the seat-rail above them, and by brackets B below, to which 105 they are held by lugs 24. Detachment proceeds in reverse order and in a similar manner. Hooks 26, are first unlocked from engagement by spring-snaps F, by depressing these latter, which is readily done, since the 110 outer ends of these springs project beyond the ends of brackets B², where they are accessible without being in the way. The front-ends of the seat-rails are at the same time manipulated so that hooks 26, move 115 first inwardly in slots 14, of bracket B², until they become free to be raised out therefrom, after which the seat-rail is pushed rearwardly as shown in Fig. 5, until lugs 25, and 24 become also free to be lifted out of the 120 slots in brackets B', and B. The seat-rail is free now and may be lifted off clear of the seat as shown in Fig. 3. It will now be seen that if use of top 17, is to be dispensed with, it is not necessary to disconnect it from 125 studs 18, on the seat-rail, or to remove the seat to get the top away from the vehicle, but the seat-rail only, with the top remaining in position on it, is disconnected and removed together with the back. This leaves 130

the seat without a back as shown in Fig. 3, in which condition however it may still be used as a seat.

If a back is desired, one may be provided as shown in Fig. 1, the seat-rail of which need not be provided with studs 18,—18, to permit connection of a top, but otherwise as to the attaching means it is precisely of the same construction and arrangement as the 10 removed rail, so that one back and its seat-rail may be readily interchanged with a similar set and connected to the seat. My arrangement also permits the top, when removed, to remain in raised position as shown 15 in Fig. 11, which is quite an advantage, since it is thus held to its shape. This is made possible because its relation with reference to the seat-rail on which it is supported and its connection thereto is in no way disturbed. 20 Neither is the connection of arm-braces E, disturbed, at any time, nor is the seat disturbed at any time, and when no extra back is desired no duplicate parts are required whatsoever. The locking - means, spring - snaps 25 F, need not be duplicated since they remain in position on the seat and serve to lock either one of the detachable sets in position.

Having described my invention, I claim as new:

- 30 1. The combination of a vehicle-seat-back, a seat-rail adapted to be connected to a vehicle seat and consisting of two parallel parts which extend forward of the back and reach also around to the rear of this latter where 35 they are notched out on their underside, and braces attached to the back and projecting rearwardly therefrom and into the notches mentioned whereby they are confined in position.
- 40 2. The combination of a vehicle-seat-back, a seat-rail adapted to be connected to a vehicle-seat and consisting of two parallel parts which extend forward of the back and reach also around to the rear of this latter where 45 they are notched out on their underside, and

braces whereby both are connected, there being two braces which project forwardly of the back and are attached to the seat-rail near its forward ends, and two braces which extend rearwardly from the back and into 50 the notches of the seat-rail mentioned in which they are confined.

3. The combination of a vehicle-seat having brackets projecting outwardly over its upper edge, there being two brackets projecting rearwardly and others projecting laterally and all of which are slotted, a seat-rail adapted to rest on these brackets and having hooks on its under-side which engage these brackets through the slots therein, part of 60 the underside of the seat-rail above the rear-brackets being notched out, a back and braces which extend rearwardly from the lower edge of the same into these notches on the seat-rail, so as to occupy a position between the seat-rail and the brackets below, they being also perforated to permit the hook on the seat-rail to pass through and to engage the bracket below.

4. The combination of a vehicle-seat having brackets projecting outwardly from its upper edge which are slotted, a back having braces projecting rearwardly from its lower edge which rest upon the brackets on the rear side of the seat and have perforations 75 which register with the slots in these brackets, a seat-rail also resting on these brackets, it being notched out above the rear-brackets, to clear the braces thereat and provided with bosses fitted to occupy the perforation in 80 these braces and hooks on the underside of the seat-rail adapted to engage the brackets through their slots whereby the seat rail is held in place on the brackets and holds thereby also the braces on the back in position between them.
